(57) CLAIM

The ornamental design for containers and cap, as shown and described.

DESCRIPTION

FIG. 1 is a perspective view of the containers and cap of my new design as seen from the top, front and right sides;

FIG. 2 is a top plan view thereof;

FIG. 3 is a front elevational view thereof;

FIG. 4 is a right side elevational view thereof, the left side elevation being a mirror image;

FIG. 5 is a rear elevational view thereof;

FIG. 6 is a bottom plan view thereof; and,

FIG. 7 is a perspective view similar to FIG. 1, wherein the front flap of the cap is in the open position.
